ATTORNEYS

UNITED STATES PATENT OFFICE.

CORWILL JACKSON, OF KALAMAZOO, MICHIGAN.

CONNECTER FOR ELECTRIC CABLES.

Application filed March 14, 1922. Serial No. 543,673.

To all whom it may concern:

Be it known that I, CORWILL JACKSON, a citizen of the United States, residing at 217 South West Street, Kalamazoo, Michigan, have invented certain new and useful Improvements in Connecters for Electric Cables, of which the following is a specification.

This invention relates to improvements in connectors for electric cables.

The main objects of this invention are:

First, to provide an improved connector for electric cables especially intended for use in driving tools; for instance, such tools as tie tampers illustrated in my Patent #1,329,049, dated Jan. 27, 1920, and another use is where considerable lengths of cable are dragged about, as in mine machinery and tools and the like.

Second, to provide an improved connector for cables which provides a very secure connection and one which minimizes the strain upon the cables and their conducting wires.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a detail view of a connector embodying the features of my invention, partially broken away for convenience in illustration and to show structural details.

Fig. II is a detail view mainly in longitudinal section on a line corresponding to line 2-2 of Fig. III.

Fig. III is a transverse section on a line corresponding to line 3-3 of Figs. I and II.

Fig. IV is a detail section on a line corresponding to line 4-4 of Fig. I, showing the arrangement of the connecting link or a pair of connectors.

Fig. V is a detail view of my improved connector adapted for a branched line.

Fig. VI is a sectional view on a line corresponding to line 6-6 of Fig. V.

In the drawing similar reference characters refer to similar parts throughout the several views and the sectional views are

taken looking in the direction of the little arrows at the ends of the section lines.

Referring to the drawing, 1 represents a conductor cable, the cable shown being provided with three of the wires 2 as it is intended for use with a three phase motor.

My improved connectors comprise a pair of members 3 and 4 having opposed channels 5 for the cable and opposed channels 6 for the connector terminal members 7 and 8. These are of the plug and socket type, being the same except that one is a plug and the other a socket to receive the plug. These terminal members are provided with sockets 9 at their inner ends internally threaded to receive the clamping screws 10, the wires 2 being arranged through the bores 11 of the clamping screws and spread out so that they are clamped in the bottom of the sockets by means of the screws. The heads of the screws are non-circular so that they may be turned down by means of a wrench securely clamping the wires. Tubular insulators 12 are provided for the terminals 7 and 8, these terminals being of soft or resilient rubber. The conductor cable 1 is also provided with a tubular casing 13 of resilient rubber.

The connector members have internal lugs 14 engaging the insulators 12 and internal lugs 15 engaging the casings 13 so that when the connector members are clamped together by means of the bolts 16, the lugs are embedded in the casing and insulators, securely binding them within the connector. The heads of the clamping screws are embraced by the insulator 12 thereby also providing a further binding means between the parts. The latch or connecting link 17 is pivoted to one connector at 18 and is provided with a hook 19 adapted to engage the transverse bolt 20. The connectors are thus effectively secured together and at the same time may be readily disengaged. The strain upon the cable is minimized by this connection and at the same time it is securely clamped so that the wires are not likely to be pulled from the terminals.

The terminals are supported so as to yield somewhat by means of the resilient insulators so that the connectors may be dragged along on the ground or over railway ties or the like without liability of injury thereto and the insulators are not cracked or broken by such usage as would be the case if they were of hard material.

In some instances I desire to use a branched connector, designated generally by the numeral 21. The structure of this is the same as described with the exception that it has Y arms 22 having channels therein to receive a part of the cable 23 intermediate its ends. This cable has a tubular casing 24 corresponding to the casing 13 and the connecting wires 25, shown by dotted lines in Fig. V, are connected to the wires 26 of the cable, as indicated by dotted lines in Fig. V, the wires 26 being continuous through the connector 21.

I thus provide a branched connector which has the advantage of securing the cable with a minimum of strain upon the wires thereof and also the other advantages, as stated, of the single line or conducting cable connectors. Other variations and adaptations will no doubt suggest themselves to those skilled in the art to which my invention relates.

Having thus described my invention, what I claim as new and desire to secure by Letters Patent is:—

1. The combination with a conductor cable, of a pair of Y connector members provided with clamping bolts and having a plurality of opposed longitudinal internal channels in the body portion thereof and opposed continuous channels in the arms thereof, a portion of said cable intermediate its ends being clamped in said arms, such portion being provided with a tubular casing of resilient material, connector terminal members having threaded sockets at their inner ends, connecting wires for the wires of said conductor cable to said terminal members, clamping screws for said connecting wires, the ends of such wires being arranged through the screws and clamped in the bottoms of said terminal sockets, said screws being provided with projecting heads, and tubular insulators of resilient material for said terminal members embracing the heads of said clamping screws, said insulators being clamped in said channels.

2. The combination with a conductor cable, of a pair of Y connector members provided with clamping bolts and having a plurality of opposed longitudinal internal channels in the body portion thereof and opposed continuous channels in the arms thereof, a portion of said cable intermediate its ends being clamped in said arms, such portion being provided with a tubular casing of resilient material, connector terminal members, connecting wires for the wires of said conductor cable to said terminal members, and tubular insulators of resilient material for said terminal members, said insulators being clamped in said channels.

3. The combination with a conductor cable, of a pair of Y connector members provided with clamping bolts and having a plurality

of opposed longitudinal internal channels in the body portion thereof and opposed continuous channels in the arms thereof, a portion of said cable intermediate its ends being clamped in said arms, such portion being provided with a tubular casing of resilient material, the ends of which project substantially beyond the ends of the arms, connector terminal members, connecting wires for the wires of said conductor cable to said terminal members, and tubular insulators of resilient material for said terminal members, said insulators being clamped in said channels with their outer ends projecting from the connector members, said connector members having internal lugs engaging said insulators.

4. The combination with a conductor cable, of a connector comprising a pair of opposed Y-shaped members provided with clamping bolts and having opposed longitudinal internal channels in the arm portions thereof and a plurality of opposed longitudinal channels in the body portions thereof, a portion of said cable intermediate its ends being disposed in the said channels of said arms, connector terminal members connected to the wires of said conductor cable, and insulators for said terminal members disposed in said channels in said body portions of said connector.

5. The combination with a conductor cable, of a connector comprising a pair of opposed Y-shaped members, a portion of said cable intermediate its ends being clamped between the arms of said connector members, the portion so clamped being provided with a tubular casing of resilient material, connector terminal members connected to the wires of said conductor cable, and tubular insulators of resilient material for said terminal members clamped between the body portions of said connector members.

6. The combination with a conductor cable, of a connector comprising a pair of opposed Y-shaped members, a portion of said cable intermediate its ends being clamped between the arms of said connector members, connector terminal members connected to the wires of said conductor cable, and insulators for said terminal members clamped between the body portions of said connector members.

7. The combination with a conductor cable, of a connector comprising a pair of opposed Y-shaped members, a portion of said cable intermediate its ends being clamped between the arms of said connector members, and connector terminal members connected to the wires of said conductor cable.

8. The combination with the conductor cables of a pair of connectors each comprising a pair of members having opposed cable channels and opposed connector terminal channels therein, connector terminal members, tubular insulators of resilient material

- 5 sleeved upon said terminal members, tubular casings of resilient material on said conductor, and cables disposed in said conductor cable channels of said members, said connector members being provided with inwardly projecting lugs engaging said resilient insulators and cable casings when the connector members are clamped thereon.
- 10 9. The combination with the conductor cables of a pair of connectors each comprising a pair of members having opposed cable channels and opposed connector terminal channels therein, connector terminal members, tubular insulators of resilient material sleeved upon said terminal members, and tubular casings of resilient material on said conductor cables disposed in said conductor cable channels of said members.
- 15 10. The combination with a conductor cable provided with a tubular casing of resilient material, connector terminal members, tubular insulators therefor of resilient material, and a pair of connector members provided with opposed channels for said conductor cable and terminal members, clamped thereon.
- 20 11. An electrical conductor connector comprising a pair of members having a plurality of opposed longitudinal channels, connector
- 25 terminal members having threaded sockets 30 at their inner ends, conducting wires, clamping screws having longitudinal holes therein through which said wires are arranged so that the ends of the wires are clamped by the screws in the bottoms of 35 said terminal sockets, said screws being provided with projecting heads, and tubular insulators of resilient material sleeved over said terminal members and embracing the heads of said screws, said insulators being 40 disposed in said channels.
- 30 12. An electrical conductor connector comprising a pair of members having a plurality of opposed longitudinal channels, connector terminal members having threaded sockets 45 at their inner ends, conducting wires, clamping screws having longitudinal holes therein through which said wires are arranged so that the ends of the wires are clamped by the screws in the bottoms of said terminal 50 sockets, said screws being provided with projecting heads, and tubular insulators of resilient material sleeved over said terminal members, said insulators being disposed in 55 said channels.
- In witness whereof, I have hereunto set my hand and seal.
- CORWILL JACKSON. [L.S.]
